UNITED STATES PATENT OFFICE.

WILLIAM H. DUSENBURY, OF NEW YORK, N. Y.

DOG-MUZZLE.

No. 872,279.

Specification of Letters Patent.

Patented Nov. 26, 1907.

Application filed July 9, 1907. Serial No. 382,842.

To all whom it may concern:

Be it known that I, WILLIAM H. DUSENBURY, a citizen of the United States, and a resident of the city of New York, borough of Manhattan, in the county and State of New York, have invented a new and useful Improvement in Dog-Muzzles, of which the following is a full, clear, and exact description.

The purpose of the invention is to provide a very simple, durable, and economic form of muzzle, and to so construct the same that it will not chafe the nose at any point, and which will also effectively prevent the nose of the animal protruding through the front 15 of the muzzle.

It is also a purpose of the invention to provide a muzzle of the character described that will be constructed almost entirely of wire, and one that can be worn with comparative 20 comfort.

The invention consists in the novel construction and combination of the several parts as will be hereinafter fully set forth and pointed out in the claims.

Reference is to be had to the accompanying drawings forming a part of this specification, in which similar characters of reference indicate corresponding parts in both the figures.

Figure 1 is a perspective view of the improved muzzle; and Fig. 2 is a longitudinal, vertical section taken about centrally through the muzzle.

The body of the muzzle is constructed from a single piece of wire of suitable gage bent upon itself to form two side members A and A' that diverge at their rear ends, and an upwardly and forwardly inclined arched head bar member B that rises from the rear 35 portions of the side bar members, and a front crossed guard section C that extends upward with a slight forward inclination from the forward end portions of the side bar members A and A', and a throat member D in the form 40 of a bar that connects the side bar members A and A' where the arched head member B is joined to them. The aforesaid single wire is formed into loops 10 at the rear ends of the side bar members A and A', which loops receive 45 links 11 adapted to carry the neck strap 12. Where the side bar members A and A' connect with the front crossed guard section C, said wire is bent upon itself to form eyes 13 to which the ends of a chin bar 14 are

secured, and said chin bar at its center is connected with the throat bar D by means of a brace bar 15.

In forming the front crossed bar section C, the wire is bent to provide two crossed members 16 and 17, formed with coils at 55 their upper portion, said coils being designated as 16^a and 17^a, and the front is straight, crossing from coil to coil to provide a connecting or bridging member 18. This guard section C constitutes one of the 60 features of the invention and serves to prevent the animal from thrusting its nose through the front end of the muzzle, and yet is comfortable, affording ample room 65 and ventilation, while the coils 16^a and 17^a render the muzzle very strong yet elastic 70 at its forward end where the greatest strength is needed.

Another feature of the invention is what I term a connecting nose strap E; this strap 75 is made from plate metal of light weight, and is provided with a loop 19 at its outer or forward end and a larger loop 20 at its inner or rear end. The loop 19 is made to grip the bridging member 18 of the crossed guard 80 section C, while the loop 20 receives the bow section of the arched head member B, and also the bowed arched member B', that extend down and are secured respectively to the rear and forward end portions of the 85 side bar members A and A', and the said loop 20 further receives a link 21 connected with a head strap 22, which in its turn has sliding connection with the neck strap 12.

A muzzle constructed in the manner above 90 described is of very simple form and is likewise very effective. The parts are but few in number, yet they are thoroughly braced and occupy such position as to render the muzzle highly protective yet prevent undue 95 chafing of the parts inclosed.

Having thus described my invention, I claim as new and desire to secure by Letters Patent,—

In a dog muzzle, a body portion comprising 100 side bar members, a connecting throat member, an upwardly and forwardly extending guard section comprising two centrally crossed members, each terminating in a coil at its upper end, a member connecting the coils, an arched head member that extends upwardly and forwardly from 105 the rear portion of the side bar members, a

flat metal strap secured at its forward end to the guard section between the coils thereof, being attached at its rear end to the upper central portion of said head member, 5 and a link carried by the rear end portion of said strap.

In testimony whereof I have signed my

name to this specification in the presence of two subscribing witnesses.

WILLIAM H. DUSENBURY.
